UNITED STATES PATENT OFFICE

CHARLES J. FUNK, OF CHICAGO, ILLINOIS, ASSIGNOR, BY MESNE ASSIGNMENTS, TO THE
TEFRA CO., OF WILMINGTON, DELAWARE, A CORPORATION OF DELAWARE

TGOOTHBRUSH

Application filed December 15, 1924. Serial No. 755,874.

My invention relates to improvements in a toothbrush of the type wherein the brush is made separable from the handle or holding member therefor whereby upon the brush 5 wearing down so that it is no longer effective or becoming soiled, it may be discarded and a new one substituted.

One object of my invention is to provide an improved holding member for the brush 10 of such construction that it may be manufactured expeditiously at low cost and entirely, if desired, from a relatively inexpensive moldable material such as celluloid, pyralin or the like.

Another object of my invention is the provision of a holding member for the brush of 15 such construction that the member will take a frictional grip upon the edges of the back of the brush, which will be ample to hold the brush properly when handled or in use when the latter is inserted thereinto, without the necessity of employing any special locking devices for that purpose.

The invention consists in the novel constructions and arrangements to be hereinafter described and claimed for carrying out the above-stated objects and such other objects as will appear from the following description of certain preferred embodiments illustrated in 20 the accompanying drawings, wherein—

Fig. 1 is a perspective view of a complete toothbrush construction embodying certain principles of my invention;

Fig. 2 is a longitudinal sectional view, on 25 an enlarged scale, of a fragmentary portion of the brush holding member shown in Fig. 1;

Fig. 3 is a sectional view taken on the line 3—3 of Fig. 2;

Fig. 4 is a perspective view of the tufted brush back;

Fig. 5 is a plan view of a fragmentary portion of a brush holding member of another construction;

Figs. 6 and 7 are sectional views taken 30 on the lines 6—6 and 7—7 respectively of Fig. 5;

Fig. 8 is a longitudinal sectional view of another modified brush holding member, 35 the handle thereof being broken off;

Fig. 9 is a sectional view taken on the line 9—9 of Fig. 8;

Fig. 10 is a longitudinal sectional view of a brush holding member similar to that shown in Fig. 8, the handle thereof also being broken off; and

Fig. 11 is a sectional view taken on the line 11—11 of Fig. 10.

Like characters of reference designate like parts in the several views.

Referring first to Figs. 1 to 4, inclusive, the brush holding member 17 is preferably integrally formed with and on one end of a handle member 18. The brush holding member is formed with a loop 19 which is 45 arranged to surround entirely the edge portions of the back 20 carrying the tufts of the bristles 21. The loop is formed so that the opening therein is somewhat larger than the tufted back of the brush. The loop at 50 its bottom side is preferably formed with an inwardly projecting perimetrical shoulder 22 to form a seat for the back of the brush. A reinforcing band 23 of any suitable resilient metal is disposed in the loop, said band being secured in the loop in any desired manner, for example, by forcing the portions 23a thereof outwardly into the material forming the ends of the loop. The distance between the side portions 23b of the band is substantially 55 less than the distance across the corresponding edge portions of the brush back 20, consequently the aforesaid side portions of the band must be forced apart when the brush back is pressed into the band. Otherwise the band in the embodiment being described 60 conforms substantially to the outline of the brush back. The material forming the sides of the loop is cut away or relieved at 19a behind the aforesaid side portions 23b of the band so that they may yield and be spread when the brush back is inserted into the band. The band portions 23b take a strong frictional grip on the side edge 65 portions of the brush back and as the band fits quite closely the other edge portions of the brush, the latter is securely held in the holding member. It will be obvious that the band and the loop may be arranged so that portions other than the side portions 70

23b of the band may be made to take a strong frictional grip on the edge portions of the brush back.

In the embodiment shown in Figs. 5, 6 and 7, the brush holding member 30 is provided with a loop 31 of some suitable elastic or resilient material into which a snugly fitting reinforcing band 32 is disposed, the band being secured to the loop in any desired manner, for example, by forcing over the portions 32a thereof onto the material forming the loop. The band 32 and its supporting loop are so arranged that the internal length of the band is substantially equal to the outside perimetrical length of the brush back; the normal configuration of the loop and the band, however, is different from that of the brush back; consequently, before the brush back can be inserted into the band, the band and the loop must be distorted slightly to conform substantially to the outline of the brush back. In the embodiment illustrated the band and loop are normally shorter and wider than the brush back; therefore, when the brush back is to be inserted into the band and loop, the sides of the loop are pressed toward each other thereby elongating the band and loop and permitting the brush back to be easily inserted.

In the construction shown in Figs. 8 and 9, the brush holding member 33 is formed with a loop 34 the internal surfaces 34a at the ends of which are normal or straight while the surfaces 34b at the sides are slightly inclined, a two-degree taper having been found satisfactory. The edge portions of the back 35 of the brush 36 are formed so as to fit snugly into the loop. It will be obvious that the brush back may be tightly wedged into the holding member thus provided therefor. The construction shown in Figs. 10 and 11 is identical with that shown in Figs. 8 and 9 except a reinforcing band 37 is disposed in the loop.

In all the constructions hereinabove described the brush holding member takes a reliable frictional grip on the edges of the back of the brush which is ample to hold the brush securely when the device is handled and when the brush is in use on the teeth. When a brush becomes unfit for further use, it may readily be removed and a new one may then be substituted. When a reinforcing band is employed, the sides and ends of the loop may be relatively thin which lessens the weight of the finished article and makes it more convenient to handle. It will be apparent to those skilled in the art that the constructions of my improved brush holding members are such that they may be expeditiously manufactured with a minimum of forming and finishing operations and of a material such as celluloid, pyralin or the like. Such materials are highly desirable because they are relatively inexpensive,

readily obtainable on the market, possess sufficient strength and elasticity for the purpose, and are easy to handle in carrying out the manufacturing operations. Furthermore, the finished articles are light in weight, attractive in appearance, require no special treatment or care to maintain them in a sanitary condition and they produce no unpleasant sensation should they strike the teeth while they are being brushed.

I do not intend to limit my invention to the details of construction shown and described, except only in so far as certain of the appended claims are specifically so limited, as it will be obvious that modifications may be made without departing from the principles of my invention.

I claim:

1. A toothbrush comprising in combination a holding member provided with a loop, an endless substantially non-stretching band secured within said loop, and a tufted back member detachably held by a frictional grip within said band when pressed into position therein.

2. A toothbrush comprising in combination a holding member provided with an unbroken annular loop having a sloping inner bearing face portion at a part of its periphery and a non-sloping inner bearing face portion at another part of its periphery, and a tufted back member having correspondingly sloping and straight edge portions held by a frictional grip within said loop when pressed into position therein.

3. A toothbrush comprising in combination a holding member provided with an unbroken annular loop having oppositely disposed and oppositely sloping inner bearing face portions at parts of its periphery and oppositely disposed parallel face portions at other parts of its periphery, and a tufted back member having correspondingly sloping and straight edge portions held by a frictional grip within said loop when pressed into position therein.

CHARLES J. FUNK.
